STORAGE TUBE

Louis Pensak, Princeton, N. J., assignor, by mesne assignments, to the United States of America as represented by the Secretary of the Army

Application August 19, 1953, Serial No. 375,246

1 Claim. (Cl. 315—12)

This invention is directed to a viewing tube, and more particularly to a charge storage device having a fluorescent screen to provide a visual display of information.

There is a class of electron discharge tubes, described completely in a copending application of M. Knoll, Serial No. 295,768, filed June 26, 1952 and assigned to the same assignee as the present invention, which utilize a fine mesh screen upon which can be established a pattern of charges corresponding to information to be reproduced for visual inspection. Within the tube a source of electron emission provides an electron discharge directed through the storage screen. On the opposite side of the screen there is mounted a fluorescent screen to receive the electron discharge and to provide a visual display thereof. The storage screen controls the amount of the electron discharge passing through it from point to point, so that the luminescent display provided by the fluorescent screen is varied from point to point, in accordance with the charge pattern on the storage screen. The pattern on the storage screen may be established by either a photocathode providing an electron image discharge or by an electron gun, whose beam is modulated in accordance with incoming signals, while the beam is being scanned over the surface of the storage screen. Such storage viewing tubes provide a greater intensified visual display than is possible with a single modulated electron beam.

However, prior to the time of this invention it has been difficult to provide bright displays on the fluorescent screen of the stored information in tubes as described above. Furthermore, it has been impossible to selectively erase any desired part of the stored picture at will.

It is therefore an object of this invention to provide an improved charge control storage tube.

It is another object of this invention to provide a charge control storage tube in which the brightness of the visual picture is greatly improved.

It is a further object of this invention to provide an improved charge control storage tube including means for selectively erasing any part of the stored picture at will.

These and other objects are accomplished in accordance with this invention by providing a charge controlled storage tube including a "viewing" electron gun and a "writing" electron gun. Arranged in operative spaced relationship with the two electron guns is an insulating storage surface and a fluorescent screen. Surrounding the envelope adjacent the storage surface is a solenoid. Due to the magnetic field from the solenoid, the electrons from both the writing gun and the viewing gun go through, or land upon, the storage surface perpendicularly to the plane of the storage surface. Since both the writing beam and the viewing beam are thus collimated the writing beam may be utilized for erasing a selected portion of the stored information.

The present invention will be better understood by referring to the following specification when read in con-

2

nection with the accompanying drawings and in which:

Fig. 1 is a sectional view of a charge controlled storage tube in accordance with this invention; and

Figs. 2 and 3 are graphical representations of conditions existing during operation of the tube of Figure 1.

Fig. 1 discloses a charge control storage tube comprising an evacuated envelope 10 having two neck portions respectively indicated as 12 and 14, symmetrically located about the axis of the tube. Within the envelope 10 neck 12 is an electron gun 16 which may be considered as the "viewing gun" and which provides a conical spray of electrons. Within the neck 14 is a second electron gun structure 18 for providing a modulated beam of electrons which is focussed and deflected down the neck 14 into the envelope portion 10. Gun 18 is considered as the "writing gun" and is also used for erasing. Mounted at the large end of the envelope portion is a target assembly 20 comprising (a) a glass support sheet 22 having, on its surface facing the electron gun 16 and 18, a thin film of transparent conductive material 24, which may be formed of metal or of a conductive compound such as tin chloride for example. On top of conductive film 24, is formed a fluorescent screen 26 which is of a phosphor material which will fluoresce under electron bombardment. Closely spaced from the surface of fluorescent screen 26, and at a distance in the order of several millimeters, is (b) a fine metal mesh storage screen 28, and (c) a second metal mesh screen 30 which is spaced beyond screen 28 at a distance in the order of 10 mm. Screen 30 may be of a woven stainless steel mesh of fineness in the order of 230 mesh per inch, while screen 28 may be a metal screen having a fineness in the order of 200 mesh per inch. Storage screen 28 is provided on the gun side with a coating 32 of dielectric insulating material, such as silica or magnesium fluoride, and having a thickness in the order of several microns.

Screen 30 is mounted on a ring 21 of insulating material fixed within the tube envelope 10, adjacent to the face plate 11 of the tube. Fixed to the insulating mounting ring 21 is an annular support ring 23, supporting, intermediate its ends, the glass target sheet 22. The fine metal mesh screen 28 is fixed across the open end of the metal support ring 23 which faces the electron guns 16 and 18. Screen 28 may be fastened to support ring 23 in any manner such as by welding, for example. Also, mounted on the insulating mounting ring 21 is a second annular metal support ring 25 across the open end of which is mounted a metal mesh screen 30 as shown in Figure 1. The conductive target film 24 of the fluorescent screen is insulated from the metal support ring 23 by the glass support sheet 22. The conductive film 24 is connected as is shown by a lead 27 to a source of potential outside the tube envelope 10. Furthermore, the metal mesh screen 28 is provided with a potential during tube operation by connecting a lead 29 to the metal support ring 23, to which metal mesh 28 is attached. In a similar manner, metal mesh 30 is connected to a source of potential by a lead 31 attached to metal support ring 25 and to conductive coating 34. Normally the electrodes 30 and 24 are maintained during tube operation at a constant potential. However, the metal mesh electrode 28, which is the storage screen, is connected, by means of lead 29, to a switch 33 which may be switched from ground to a source of potential as shown. Each of the metals of target assembly 20 is preferably made of some non-magnetic material such as some of the stainless steels or titanium.

The viewing gun 16 consists of a cathode electrode 7 having an electron emitting coating on its surface facing screen 20. A control electrode 13, and an accelerating electrode 15 are mounted successively along the axis of

gun 16 and between cathode 7 and screen 20. These electrodes are maintained, during tube operation, at appropriate voltages to form the electron emission from cathode 7 into a wide beam or spray 44 of electrons. The inner surface of the envelope 10 is coated by a conductive coating 34 of colloidal graphite adjacent to the electron gun 16. Coating 34 may be maintained at the same potential as the accelerating electrode 15 of gun 16, by means of lead-in 31.

Electron gun 18, in like manner, consists of a cathode electrode 19 and a control grid electrode 35 enclosing cathode 19. Spaced along the gun axis toward the target are in order, a first, second, and third accelerating electrodes 37, 39, and 41 respectively. Accelerating electrodes 37 and 41 are connected together as shown and to a source of potential while electrode 39 is connected to a separate source for focussing. The wall coating 34 extends into the neck 14 of the writing gun 18 and forms a unipotential region in which the electrons of gun 18 travel as a beam 38 onto the target 20. Incoming signals may be applied to the control grid 35 by any appropriate circuit means 43.

The voltages of the several electrodes disclosed in Figure 1 are illustrative of voltage values which can be used during operation of the tube of the type described. However, these voltages are not limiting. For example, mesh grid 30 may be operated between 200 volts and 2,000 volts positive relative to ground. The conductive coating 24 may be operated within a range of 200 volts to 2,000 volts positive relative to ground, while the storage mesh 28 may be varied between zero and a minus 200 volts relative to ground.

As shown in Figure 1, the metal mesh grid 30 is operated at around 1,000 volts positive with respect to ground or with respect to the cathode potential of the viewing gun 16. Also, the conductive coating 24 of the fluorescent screen is operated at close to 8,000 volts positive with respect to ground or viewing gun cathode potential. The potential of the metal mesh 28, supporting the insulating coating 32, is operated at a negative voltage of 80 volts, or at ground, which will be explained hereinafter.

Surrounding the envelope 10 adjacent the storage film 32 is a solenoid 36 that is energized by a direct current in the usual manner. As is well known the magnetic lines of force of such a coil are curved and are all perpendicular to the plane surface that is parallel to the planes in which its coils are wound, and that is located on the effective center of its windings. The solenoid 36 is arranged so that this plane is the location of the storage surface 32.

The electron beam 38 from the writing gun 18 is scanned over the surface of the storage screen electrode 28 in any well known manner, as for example, by two pairs of electrostatic deflection plates 40 and 42, respectively. As is well known, the pairs of plates 40 and 42 may be each connected to sources of saw-tooth voltages for providing line and frame scanning of the beam over the surface of the mesh screen 28.

Referring to Figure 3 there is shown a schematic diagram of the effect the solenoid 36 has on the viewing and writing beams 38 and 44 respectively. When the high velocity beams pass through the apertured electrode 30 they enter a decelerating region and are slowed down to a few volts velocity near electrode 32. Due to this slow movement, the electrons are in the magnetic field for a considerable time and thus the magnetic field of the solenoid 36 is very effective on the direction of the electrons, and the electrons tend to follow the magnetic lines of force. It is for this reason that the electrons of both beams go through, or land on, the storage film 32 substantially perpendicular thereto. Thus, either beam of electrons is collimated regardless of the angle of approach to the storage film 32.

In the tube described and shown in Figure 1, film 32 may be silica and electrons striking a silica film of this

type with energies above 50 volts, called the first crossover potential, will initiate a secondary emission greater than unity, i. e. the number of secondary electrons leaving any point of the dielectric surface 32 is greater than the number of electrons of beam 38 striking that point. Depending upon the potential at which screen 28 is set, electrons of beam 38 will drive the insulating surface 32 to a uniform potential. A fraction of a second only is required to drive all of the surface to a uniform potential.

To prepare the target for storing a charge on the insulating coating 32, it is necessary to establish a uniform potential over all of the film 32. This is done by placing switch 33 to the -80 volt position and turning on the writing gun 18. The electrons from the writing gun 18 strike the insulator surface at a velocity of 20 volts, i. e. below first crossover potential, and drive all positive insulator areas negative to the potential (-100 volts) of the cathode 19. When this has been done, switch 33 is changed to the ground position and, due to the thinness of the insulating film 32, the film 32 is capacitively coupled to the back plate potential so that film 32 "follows" the back plate and assumes a potential of -20 volts, i. e. the difference of the -100 volts and -80 volts remains. Now when the viewing beam 44 is turned on, the electrons, which are accelerated through the positive collector screen 30, enter a retarding electric field adjacent the surface of film 32 and are turned back to the collector screen 30 by the negative potential of the film. When the potential of insulating film 32 is -20 volts the field of film 24 does not penetrate through the screen 28 to attract the electrons to the fluorescent screen 26. This is shown graphically by Figure 2.

The beam 38 of the writing gun is then turned on again and scanned over the surface of the insulating film 32 while being modulated by incoming signals applied to the control grid 35 by the input circuit 43. The writing beam 38 strikes the insulating coating at energies around 80 volts, which is above the first crossover potential of the secondary emission curve of the silica film 32. In this manner beam 38 initiates secondary emission from the silica surface greater than the number of electrons striking the surface from beam 38, and in those areas where the beam strikes, the silica surface is driven in a positive direction by the secondary emission from its potential of a -20 volts toward the viewing gun cathode potential or ground. The strength of beam 38 determines the amount that the screen 28 is driven in a positive direction with full brightness occurring when screen 28 is at ground potential. However, no point of the surface of film 32 can be driven by beam 38 more positive than ground, since the spray of electrons 44 will land on the film at that point and drive it back to ground potential or slightly below. In those areas of the silica film 32 which are driven in a positive direction toward ground by beam 38, the positive field of the fluorescent screen 24-26 will now penetrate and draw the low velocity electrons of beam 44 through the mesh 28. These electrons of beam 44 which pass through mesh 28, are highly accelerated by the intense positive field between mesh 28 and film 24 and will strike the fluorescent screen 26 at high velocities to cause luminescence of the screen. This luminescence will only appear from portions of screen 26 adjacent those areas of the storage screen 28 struck by the writing beam 38. Where beam 38 does not strike film 32, the film remains negative and the positive field of the fluorescent screen can not penetrate through screen 28 to draw beam electrons 44 through to the fluorescent target surface.

This type of "writing," graphically represented in Figure 2, provides a picture on the fluorescent screen, which is dark in the unwritten areas and light or bright in the written areas. The background of the picture will be black and the "written" areas will be white. Theoretically, once a signal has been written on the charge storage screen 28, it may be seen indefinitely on the

luminescent screen 26 since with the mode of tube operation as described above, the charged areas are never discharged by the low velocity beam 44 because the electrons of spray 44 penetrate through the field of mesh 28. Actually, however, the stored charge on film 32 is gradually dissipated by spurious positive ions in the tube.

In accordance with this invention, the stored signal on the insulating film 32 may be selectively erased and the surface of the film rewritten on. Erasing may be done as described above by shifting the potential of mesh screen 28 in a negative direction, i. e. -80 volts, until the electrons of the writing beam 38 strike film 32 with energies below the first crossover potential of the secondary emission curve of the insulating material. At this potential of electrode 28 any area of the surface of the insulating film 32 can be scanned by beam 38 and thus driven negative toward the potential of the writing gun cathode 19. Then, the screen 28 is reset to its ground potential and a new signal may be written down on the selected areas of the surface of the storage screen 32. Thus, any selected area may be erased by scanning this selected area with beam 38 when switch 33 is on the -80 volt position. Both the viewing gun electrons 44 and the writing gun beam 38 enter the target area perpendicular to the film 32 thus, the picture definition obtained is of an improved quality. The reason for this may be better understood by referring to Figure 3 wherein the beams are shown as arriving from exaggerated off-axis positions. Assuming that the target 32 has been written on by the writing beam 38 in such a manner that the insulator target 32 is -18 volts with respect to ground. It is obvious that electrons having such small energies could not be seen if the electrons 44 from the viewing gun 16 were arriving at an angle. This is due to the fact that, with such low energies, if any of the component of the velocity is not along the tube axis the energies are not sufficient to go through the apertures in insulating film 32 and the electrons would return to the collector electrode 30. However, due to the effect of the magnetic field of solenoid 36 the electrons arrive perpendicular to target film 32 so that all of their energy is in a direction along the tube axis. Thus any electron from the viewing gun cathode 7, regardless of its angle of approach or location with respect to the target 28 arrives at the target assembly 20 as intended.

A further advantage of the new and improved tube of this invention is that the writing beam 38 may now be used for selectively erasing any part of the stored information. In order to do this the writing beam 38

must land on the storage surface 32 at a velocity below first crossover potential in order to drive the storage surface negative below adjacent areas. Because of the fact that, without solenoid 36, some of the electrons of beam 38 would approach the target at different angles, not all of the surface would be driven to the writing gun cathode 19 potential and uniform erasure would not be possible. However, due to the field of solenoid 36, every electron that leaves the writing gun cathode 19 lands on the storage surface 32 below first crossover potential and perpendicularly thereto, thus providing uniform erasure in any of the selected areas.

Although the invention has been disclosed in connection with specific details of preferred embodiments thereof, it must be understood that such details are not intended to be limitative of the invention except in so far as set forth in the accompanying claim.

I claim:

An electron discharge device comprising an elongated envelope, a target assembly in one end of said envelope, said target assembly comprising a substantially flat transparent support member having a transparent conductive coating on one surface thereof, a layer of phosphor material on said conductive coating, an apertured conductive mesh screen spaced closely adjacent to and substantially parallel with said phosphor material, an insulating coating mounted on the solid portions of said mesh screen and having apertures therein in registry with the apertures in said screen, an apertured collector electrode spaced closely adjacent to and substantially parallel with said insulating coating, a first electron gun in the other end of said envelope for producing a low velocity electron beam directed toward said target assembly, a second electron gun in said other end of said envelope for producing a stream of electrons directed toward said target assembly, a coil around said envelope and adjacent to said insulating coating for collimating said electron beam and said stream of electrons, said coil extending a substantially equal distance on each side of the plane of said insulating coating, whereby both said electron beam and said stream of electrons arrive at said plane in a path substantially perpendicular to said plane.
